UNITED STATES PATENT OFFICE.

WILLIAM OTIS MOODY, OF LA GRANGE, ILLINOIS.

DRIVING BOX AND SPRING SADDLE.

Application filed November 18, 1925. Serial No. 69,769.

This invention relates to driving box and spring saddle construction for locomotives and has for its principal objects the provision of improved forms of these parts which will give the saddle an increased bearing surface on the box, prevent rocking of the saddle in service, and insure a constant or exact distance from the spring seat on the saddle to the center of the axle.

10 It should be understood that in the conventional arrangement heretofore used the legs of the driving box saddle are fitted into recesses cast in the top of the driving box. The bottom of these recesses, of course, 15 cannot be finished except by chipping, an operation which, as is well known, does not lend itself to accurate work.

I overcome the foregoing difficulty and attain the advantages mentioned by providing 20 a driving box and saddle structure in which the meeting or bearing faces or surfaces are accurately machined.

I have illustrated the invention in preferred form in the accompanying drawings, 25 wherein

Fig. 1 is a cross section through a driving axle looking outwardly toward the driving box and the driving box saddle with a certain portion of the upper part of the driving 30 box broken away and shown in section;

Fig. 2 is an enlarged view showing the top of the box in longitudinal section with the legs of the driving saddle cooperating therewith;

35 Fig. 3 is a plan section through the legs of the saddle showing the manner in which they fit into the driving box;

Figs. 4 and 5 are similar respectively to Figs. 2 and 3 but illustrate a slight modification of the invention.

In the drawings the driving box 1 is shown mounted within the pedestal jaws 2 and 3 with the pedestal binder 4 therebelow.

In the top of the box is a hollow or depressed portion 5 the lateral edges 6 of which are accurately machined. The saddle with its legs 7 cooperates with the recess 5 and the machined surfaces 6 in the following manner. The bottom 8 of each leg is accurately machined to cooperate with the machined surfaces 6. Near the bottom the legs 7 inwardly and downwardly projecting positioning lugs 9 extend into the space between the lugs 10 on the lateral walls of the depression 5.

It will thus be seen that the meeting or

bearing surfaces between the saddle and the box are machined surfaces which can be made as accurate as desired, the lugs 9 simply serving to position the saddle on the box without in any way helping to carry the load by bearing on the bottom of the recess 5.

In this manner the saddle can be given an increased bearing surface on the box, 65 rocking will be prevented, and the distance from the spring seat 11 to the center of the axle 12 can always be maintained an exact distance. The description so far has applied to Figs. 1 to 3 inclusive. 70

In the modification of Figs. 4 and 5 the legs 7^a of the saddle continue straight on down into pockets 13 at the sides of the recess 5^a and thereby serve to position the saddle on the box. On the outside of each leg 7^a is a projection or buttress 14 the bottom face 15 of which is the bearing face and is adapted to be machined for cooperation with the corresponding machined bearing face 16 on the top of the box 1. The net result is 80 exactly the same as in the first type and in both types the projection from the saddle into the recess in the top of the box is simply for positioning purposes. 85

I claim:—

1. A driving box and a spring saddle having machined bearing faces and interengaging positioning means out of the plane of the machined surfaces.

2. The combination of a locomotive driving box having a machined saddle bearing surface, a spring saddle having a machined surface cooperating with that on the box, and positioning means on box and saddle out of the plane of the machined surfaces. 90 95

3. The combination of a driving box having a recess in its upper surface, a machined bearing face adjacent said recess, a spring saddle having a machined lower face adapted to bear on the machined face of the box, and a positioning lug on the saddle projecting down past the machined faces into said recess. 100

4. The combination of a driving box, a spring saddle, a machined bearing face on the box, an opposed machined bearing face on the saddle, and interengaging positioning means on box and saddle. 105

In testimony whereof, I have hereunto signed my name.

WILLIAM OTIS MOODY.
